M. B. OKUN.
BEDSTEAD CORNER FASTENING.
APPLICATION FILED FEB. 27, 1916.

1,185,236.

Patented May 30, 1916.

UNITED STATES PATENT OFFICE.

MORRIS B. OKUN, OF CHICAGO, ILLINOIS, ASSIGNOR TO THE SENG COMPANY, OF CHICAGO, ILLINOIS, A CORPORATION OF ILLINOIS.

BEDSTEAD CORNER-FASTENING.

1,185,236

Specification of Letters Patent.

Patented May 30, 1916.

Application filed February 27, 1915. Serial No. 10,902.

To all whom it may concern:

Be it known that I, MORRIS B. OKUN, a citizen of the United States, residing at Chicago, in the county of Cook and State of Illinois, have invented new and useful Improvements in Bedstead Corner-Fastenings, of which the following is a specification, reference being had to the accompanying drawings, forming a part thereof.

10 The purpose of this invention is to provide an improved form of metal corner fastening for bedsteads.

15 It consists in the elements and features of construction shown and described, as indicated in the claims.

20 In the drawings: Figure 1 is an inner side elevation of a fitting embodying this invention. Fig. 2 is a section at the line, 2-2 on Fig. 4. Fig. 3 is a plan view. Fig. 25 Fig. 4 is a section at the line, 4-4 on Fig. 1. Fig. 5 is a view similar to Fig. 1, showing a modification. Fig. 6 is a section at the line, 6-6, on Fig. 5. Fig. 7 is a detail section at the line, 7-7, on Fig. 5. Fig. 8 is an elevation of an escutcheon plate. Fig. 9 is a perspective view of a detachable terminal for the cross rail in slightly modified form from that shown in Fig. 2. Fig. 10 is a section at the line, 10-10, on Fig. 5, showing 30 the corner fastening secure to a wooden corner post.

35 In the structure shown in the drawings, referring to Figs. 1, 2 and 3 and 4, 1 is a corner-post, 2 is a folded metal fitting or housing bolted to the corner-post and adapted for receiving, and having rigidly secured to it as hereinafter described, the cross-rail, 3, and the side-rail, 4. The general construction of this housing or fitting, 40 2, is the same as shown and described in my Patent No. 1,126,068, dated January 26, 1915, and may be briefly described as formed of a single piece of metal plate cut and folded to form a back, 2^a, outer side, 2^b, inner side, 2^c, front edge, 2^d, and top, 2^e.

45 The front, 2^c, has an aperture, 2^f, through which the side-rail, 4, is inserted; and the inner side, 2^c, front edge, 2^d, and top, 2^e, lug, a, which guides the clamping yoke, 5, lodged within the housing, and constructed for clamping in place the side-rail, 4, by means of the clamping bolt, 6, which is inserted down through the top plate, 2^e, and

provided with a wing nut, 7, below the pock for clamping the yoke up against the side-rail. This construction for holding and securing the side-rail is fully described in my said Patent No. 1,126,068. The novel features of the present construction relate to the means for connecting the cross-rail to the housing, 2. In the form shown in Figs. 1, 2 and 3, the horizontal flange of the angle iron cross-rail, 3, is extended endwise to form a lug, 3^a, which laps on top of the housing, and has a square aperture, 3^b, for the square shoulder of the bolt, 6, which takes through said aperture in the lug in extending through the housing for the purpose of clamping the side rail as described, so that the bolt in performing its function of clamping the side rail, also secures the cross-rail. For further security of the cross-rail rigidly to the housing, the inner side-wall, 2^c, has a vertically-extending slot, 2^k, and the vertical flange of the angle iron cross-rail, 3, is cut away to leave it projecting in the form of a hooked lug, 3^c, adapted to enter the slot, 2^k, and engage by means of the notch, 3^d, in its lower edge, the lower margin of the slot, 2^k, thus effecting an engagement with the inner side-wall, 2^c, adapted to prevent endwise displacement of the cross-rail. Inasmuch as the bolt, 6, is tight in its place only when the side-rail is inserted in the housing so as to be clamped by the bolt and the clamp-yoke, 5, it will be seen that the bedstead end frame with the housings, 2, mounted upon both posts and connected by the cross-rail, would not be suitably tied together and stiffened by the cross-rail, as is the design and intention of the construction without the insertion of the side-rail, unless some means were provided for holding the cross-rail in the position in which it would be held by the tightening of the bolt,—that is, so that the cross-rail cannot lift up to disengage its notch 3^d, from the margin of the slot, 2^k, of the housing inner side plate. In order to remedy this defect a small lug, 3^m, is struck out of the vertical flange of the cross-rail, 3, in position to lie against the outer surface of the inner side plate, 2^c, of the housing, and be secured thereto by a screw, 9, set through a hole in said lug and into a tapped hole in said inner side plate.

of the housing. Since the only function of this lug and its screw attachment to the housing is to prevent displacement upwardly of the cross-rail, a small lug and

5 small screw are adequate for the purpose.

In the form shown in Figs. 4, 5 and 6 and 7, the horizontal flange of the cross-rail is constructed in the same manner as in the form shown in Figs. 1, 2 and 3 and 4 10 for being engaged by the bolt, 6; but instead of the provision shown in Figs. 1, 2 and 3 for engaging the vertical flange of the cross-rail with the housing, a lug 2^c, is struck outwardly from the inner side-wall, 15 2^c, of the housing, in position to be lapped by the vertical flange of the cross-rail and bolted or riveted thereto. Preferably the lug is positioned for lapping on the inner side of the vertical flange of the cross-rail, 20 as shown.

Since these devices are usually manufactured to be furnished to bedstead manufacturers, and to be embodied by the latter in their bedsteads, it is sometimes desirable to construct them so that the cross-rail need not be furnished with the housing or fittings, but that on the contrary, the fittings may be sent out complete ready to be attached or have attached to them an 25 angle iron cross-rail of any dimension (within the range of variation which is usual), the cross-rail requiring to have only two bolt or rivet holes drilled in it so as to secure it to the fitting. For this purpose 30 there is provided a clip, 10, which is an angle iron plate having the terminals similar to those which have been described as formed upon the two flanges of the angle iron cross-rail in Figs. 1, 2 and 3 and 4, 35 and having bolt or rivet-holes, 10^a, 10^b, in the two flanges, prepared for bolting or riveting an angle iron cross rail to this clip. When this clip is provided, it can be made of 40 suitably mild steel to admit of having the lug of the horizontal flange which laps on top of the housing and receives the bolt, 6, struck upwardly from the plane of the said horizontal flange to a distance equal to the 45 thickness of the metal of the housing, as seen in Fig. 7. When made in this form, it will be seen that an angle iron cross-rail applied outside the clip, will have its horizontal flange in the same plane as if it were 50 formed as in the other figures, that is, with the lug formed on the end of the horizontal flange of the angle iron cross rail itself, and in the same plane with that flange for lapping on top of the housing; or if the angle 55 iron bar is applied inside the clip, the horizontal flange of said cross-bar stands in the same plane as the horizontal flange or upper edge of the side rail secured by the clamp yoke, 5, and bolt, 6. The employment 60 of this clip, therefore affords opportunity 55 for choice of position of the cross-rail at

either of the two positions, each of which has its advantages.

In order to adapt the housing, 2, to be applied to the corner-posts, either round or square, and of any dimension round or square, and particularly to adapt such housings for use upon metal corner-posts of comparatively light tubing, whose thickness is not sufficient to afford a secure fastening by means of bolts engaging merely the metal of the tubing, there are provided escutcheon plates, 15, for square corner-posts, and 16, for round corner-posts, having upon their outer face a bead, 17, which defines the seat for the back of the housing, 2, and bolt-holes, 18, within the limits of the seat to match the bolt holes of the housing through which the bolts, 19, are inserted to bind it to the post; and in conjunction with such escutcheon plate there is applied on the inside of the tubular corner-post a corrugated reinforcing or washer plate, 19^a, the bolts for securing the housing to the corner-post taking through the escutcheon plate, the metal of the tubular corner posts, and the 80 clamping or washer plate, all the parts being clamped to the post by the same bolts. By the expedient of providing escutcheon plates which may be made of various widths for various dimensions of square corner-posts, and with a marginal flange, 15^a, to clamp over the corners of the square corner-post, and which may be made of various inner curvatures to fit the different sizes of round corner-posts, the same housing may 85 be applied upon all sizes of corner-posts, both round and square. To adapt these metal housings to be used upon wooden corner posts, a plain escutcheon plate 21, with beads, 21^a, to define the seat for the back 90 of the housing, bolt holes registering with the bolt holes of the housing, are interposed between the housing and the wooden corner-post, both the housing and the escutcheon being secured to the corner-post by 95 bolts, 22. The escutcheon plate when provided on wooden corner-posts in this manner, not only affords an adequately broad bearing for the housing upon the post, which the back of the housing alone might 100 not be of adequate area to do, but in addition it prevents the marring and possible 105 tendency to split the post which would sometimes result from binding the housing with the curved or hollow back with which 110 it is formed for mounting upon round tubular metal posts directly against the wood.

I claim:—

1. A corner-post fastening consisting of a folded sheet metal housing, having its front 125 edge wall apertured for receiving a side rail; means for clamping such side-rail to the housing, comprising a bolt inserted through the top wall of the housing, and a cross-rail having its terminal comprising a 130

horizontal and a vertical flange, the horizontal flange having an endwise projection adapted to lap on the top of the housing and to be bound to the latter by the clamping bolt which secures the side rail, the inner side wall of the housing having means for engaging the vertical flange against endwise displacement of the side-rail.

2. A corner-post fastening comprising in combination, a folded sheet metal housing having its front edge wall apertured for receiving a side-rail; means for clamping such side-rail to the housing, comprising a bolt inserted through the top of the housing, and a cross-rail having a terminal for engaging the housing, comprising a horizontal and a vertical flange, the horizontal flange having an endwise projection which laps upon the top of the housing and is adapted to be clamped thereto by the bolt which clamps the side-rail, the side wall of the housing having a vertical slot, and the vertical flange of the cross-rail terminal being formed for hooking inwardly through and downwardly to engage the margin of slot, and to come into such engagement when the projection of the horizontal flange is lodged down upon the top of the housing.

3. A corner-post fastening comprising in combination, a folded sheet metal housing having its front edge wall apertured for receiving a side-rail; means for clamping such side-rail to the housing, comprising a bolt inserted through the top of the housing, and a cross-rail having a terminal for engaging the housing, comprising a horizontal and a vertical flange, the horizontal flange having an endwise projection which laps upon the top of the housing and is adapted to be clamped thereto by the bolt which clamps the side-rail, the side wall of the housing having a vertical slot, and the vertical flange of the cross-rail terminal being formed hooking inwardly through and downwardly to engage the margin of slot, and to come into such engagement when the projection of the horizontal flange is lodged down upon the top of the housing, said vertical flange having a lug struck and folded inwardly therefrom, lapping against the outer surface of the inner side wall of the housing and means for securing it thereto.

4. In a bedstead corner fastening, in combination with a housing adapted to receive a side rail and a cross rail, having a back wall for mounting against the corner post which is longitudinally or vertically corrugated, forming a transversely concave seat facing toward the post; an escutcheon plate which forms a seat spanning the entire area of the back wall of the housing, and whose lateral extent exceeds that of said back wall, said escutcheon plate having longitudinal or vertically extending beads

or corrugations which form lateral boundaries for the seat of the housing on the escutcheon plate and stops against the lateral movement of the housing on said plate; a washer plate adapted to be entered inside of the hollow corner post; the housing, escutcheon and washer plate having registering bolt holes, and bolts extending through the same and through the corner posts for clamping the housing and washer plate onto opposite sides of the wall of the corner-post, said bolt holes being at the crest of the longitudinal or vertically-extending corrugation of the back wall of the housing.

5. In a bedstead corner fastening, in combination with a housing adapted to receive a side rail and a cross rail, having a back wall for mounting against the corner post which is longitudinally or vertically corrugated, constituting said wall inwardly transversely convex and forming a transversely concave seat facing toward the post; an escutcheon plate which forms a seat spanning the entire area of the back wall of the housing and whose lateral extent exceeds that of said back wall, said escutcheon plate having a medially situated longitudinal or vertically extending outwardly convex corrugation fitting said concave seat of the housing, and having longitudinal or vertically extending beads or corrugations which form lateral boundaries for the seat of the housing on the escutcheon plate and stops against the lateral movement of the housing on said plate, said housing and escutcheon plate having bolt holes which register when the housing is seated on the escutcheon plate between said stops, and bolts extending through the same and through the corner posts for clamping the housing and escutcheon thereto, said bolt holes being at the crest of said longitudinally-extending and mated corrugations of the housing and escutcheon plate.

6. In a bedstead corner fastening, in combination with a housing adapted to receive a side rail and a cross rail, having a back wall for mounting against the corner-post which is longitudinally or vertically corrugated, forming a transversely concave seat facing toward the post; an escutcheon plate which forms a seat spanning the entire area of the back wall of the housing, and a washer plate adapted to be entered inside of a hollow corner-post, having a longitudinal corrugation transversely concave toward the wall of the post, and forming at its lateral limits longitudinally-extending seats bearing upon the wall of the post opposite the corresponding vertical or longitudinal corners of the back of the housing, the housing, escutcheon and washer plate having registering bolt holes and bolts extending through the same and through the

1,185,236

corner-post for clamping the housing and
the washer plate onto opposite sides of the
wall of the corner-post, said bolt-holes
being at the crests of the longitudinal cor-
rugations of the back and the washer-plate,
respectively.

In testimony whereof, I have hereunto set

my hand at Chicago, Illinois, this 23 day
of February, 1915.

MORRIS B. OKUN.
